UNITED STATES PATENT OFFICE

FRANK MESKER, OF ST. LOUIS, MISSOURI, ASSIGNOR TO MESKER BROTHERS IRON COMPANY, OF ST. LOUIS, MISSOURI, A CORPORATION OF MISSOURI

COMBINED WINDOW AND COAL HOPPER

Application filed December 14, 1925. Serial No. 75,341.

This invention relates to new and useful improvements in combination windows and coal chutes, and the objects of the invention are to provide a window construction which admits maximum amount of light to the coal bin and can be utilized as a coal chute, there being a coal hopper provided within the window frame, which hopper can be swung in position to protect the window sill and guide the coal through the window and which when not used can be folded inwardly so as not to obstruct the admission of light through the window opening.

Further objects of the invention are to provide unitary window construction combining the window frame and the lintel, both of which are formed of steel construction thereby providing a strong and durable structure which can be readily placed in position with a minimum amount of labor, and is durable and economical to manufacture.

Other objects of the invention are to provide a basement or coal bin window having a pivotally mounted sash controlled from the inside and which can be opened to provide maximum ventilation and is removable when it is desired to use the window as a coal chute.

With these and other objects in view, my invention consists in certain novel features of construction and arrangement of parts, hereinafter more fully described and claimed and illustrated in the accompanying drawings, in which

Figure 1 is a front elevational view of the combined window and coal hopper and looking against the outside face thereof.

Figure 2 is a top plan view partly in section.

Figure 3 is a vertical section taken on lines 3-3 of Figure 1 and showing the sash in full lines in closed position and in dotted lines in open position, and the coal hopper folded inwardly.

Figure 4 is a similar view but showing the sash removed and the coal hopper moved outwardly into coal receiving position.

Figure 5 is a vertical cross section taken through the upper corner of the window structure.

Figure 6 shows a modified form of mounting the coal hopper.

Heretofore, most of the coal chutes have been formed with a solid closure member without any provision being made for the lighting and ventilation of the coal bin. In the few instances where the closure member was glazed, the hopper located within the window frame was so positioned that the greater part of the glazed area was covered or obstructed by said hopper.

In the present invention, the combined window and coal chute provides the three essentials for the coal cellar, namely, light, ventilation, and the coal chute. The window and the sash frames are formed of steel and angle irons, each being formed of a single bar of suitable cross section bent into proper shape. A sheet metal casing frame is secured to the window frame and a lintel is secured to the upper side of the window frame and the casing frame, thereby eliminating the use of any extraneous pieces in the construction of such windows and coal chutes for coal cellars.

Referring by numerals to the accompanying drawings, 10 indicates the window frame formed of a single piece bar preferably T-shape in cross section and bent into proper shape with the ends secured together. The web portion 11 of the bar 10 is disposed laterally and inwardly and the flange portions 11^a and 11^b are disposed vertically and form the frames of the window frame. In the vertically disposed portions of flange 11^a are formed a pair of opposed notches 12 in which are received offset portions 14 of a glazed sash 15. The sash frame is formed of a single piece bar T-shape in cross section, having the web portion 16 presented laterally and outwardly in opposed relation to the web portion 11. The vertically disposed flanges 15^a and 15^b lie in a plane parallel to the flanges 11^a and 11^b and offsets 14 are formed in the vertically disposed portions of flanges 15^a and 15^b whereby the upper and lower portions of flanges 15^a and 15^b are disposed on the opposite sides of flanges 11^a, the upper portions of flanges 15^a and 15^b being, in the present instance, arranged inwardly of flange 100

11^a and the lower portions of flanges 15^a and 15^b being disposed outwardly of flange 11^a.

Offsets 14 and notches 12 form pivotal mounting for sash 15 so that the latter can be swung into open position as shown in dotted lines in Figure 3. When in open position, sash 15 can be removed from the window frame by withdrawing said sash in the direction indicated by arrow A. A gravity-actuated latch 17 is pivotally mounted on the upper horizontally disposed flange portion of the sash and is adapted to engage a notch formed in the upper web portion of the window frame so as to lock the sash in closed position. A ring 18 is secured to the muntin of the sash and provides suitable means for engaging the sash when it is desired to operate the latter from the outside or to remove it.

20 A casing frame 19 formed of sheet metal bent into U-shape with the ends turned outwardly as indicated at 19^a is secured at its forward edge to the web portion 11 of window frame 10 by means of rivets 20 and is of 25 a depth co-extensive with the depth of the window opening in the wall, thereby forming a metal lining for said window opening. A lintel 21 is placed on the overhanging ends 19^a of casing frame 19 and is secured thereto by rivets or other suitable fastening devices 22, while rivets 24 secure the forward edge of the lintel to the horizontally disposed top web portion of the window frame. This lintel is provided with reinforcing ribs 25 which 35 strengthen the lintel, and the inner edge of said lintel is turned downwardly as indicated at 21^a while the ends of the lintel project a suitable distance beyond the window frame as indicated at 21^b.

40 A coal hopper 26 is pivotally secured by 45 hinges 27 to the horizontally disposed sill portion 19^b of casing frame 19. Said hopper is provided with side walls 28 terminating in wings 28^a, and the outer edge of said hopper is turned in a direction opposite to said walls 28 as indicated at 29. When hopper 26 is not 50 in use, it occupies the position shown in Figure 3 in which position portion 29 extends upwardly and side walls 28 are presented downwardly and rest against the edge of sill portion 19^b of casing frame 19. When in this 55 position, hopper 26 is out of the way and does not interfere with the operation of the sash and does not obstruct the light admitted through the window panes of the sash. A 60 pair of spaced T-irons 30 is transversely disposed in hopper 26 and each iron is secured thereto by rivets 31. These irons are arranged opposite to walls 28 and are adapted 65 to rest on the lower upwardly presented horizontal flange of the window frame and serve to space the hopper therefrom.

In Figure 6 is shown a modified construction wherein the hopper is provided with laterally projecting pins 32 which are pivotally

arranged in the sides of the casing frame 19.

When it is desired to use the coal hopper, latch 17 is moved out of locking position and sash 15 is moved into open position as shown in dotted lines in Figure 3, whereupon said sash can be removed from the window frame. Upon the removal of the sash, hopper 26 can be moved about its pivotal mounting 27 to occupy the position shown in Figure 4, in which position the hopper extends outwardly and irons 30 rest on the upwardly presented edge of the lower horizontal flange 11^a and side walls 28 are presented upwardly so as to prevent coal from falling to either side of the hopper. The laterally bent portion 29 serves as reinforcing means for the hopper. Hopper 26 is of sufficient length that when in extended or open position, it projects outwardly a sufficient distance to overhang the window sill and protect it against injury.

After discharging coal through the chute, the glazed sash is replaced in position in the window. This replacement is performed from the outside and it is only necessary to set the sash into the grooves or notches 14 and pull at ring 18 inwardly and then upwardly, whereupon the sash is locked tight by the gravity latch 17. The coal window and chute are complete in themselves and may be used either with or without the hopper. The provision of the hopper is optional, however, arrangements are made in the construction of the windows for the subsequent attachment of the hopper after the installation of the window. Any number of reinforcing ribs 25 may be used in the construction of lintel 21 and the reinforcing flange 21^a may be disposed in any suitable direction.

While I have shown and described the preferred form of my improved coal window and chute, it is obvious that various changes in the construction and arrangement of parts of my improved coal window and hopper can be made without departing from the spirit of my invention.

I claim:

1. A combined window and coal hopper comprising a window frame, a casing frame secured thereto, and a coal hopper pivotally mounted at one end to the sill portion of said casing frame and movable inwardly thereagainst into inoperative position so as not to obstruct said window frame opening said coal hopper being movable outwardly into a coal-receiving position, in which position it extends outwardly past said window frame and is arranged above the window sill to protect the latter against injury.

2. A combined window and coal hopper comprising in combination a window frame of a single piece bar bent to proper shape and of suitable cross section, a casing frame of sheet metal secured to said bar and projecting rearwardly therefrom, a coal hopper having its inner edge pivotally mounted on

the sill portion of one of said frames and movable inwardly against the sill portion of said casing frame into inoperative position and outwardly over the sill portion of said window frame into operative or coal-receiving position for discharging the same through said window, and angle irons secured transversely to the underside of said hopper for reinforcing the latter and supporting it on the sill portion of the window frame when in operative position.

3. A combined window and coal hopper comprising in combination a window frame of a single piece bar bent to proper shape and of suitable cross section, a casing frame of sheet metal secured to said bar and projecting rearwardly therefrom, a coal hopper pivotally mounted at its inner edge to the sill portion of said casing frame and movable inwardly thereagainst into inoperative position and outwardly over the sill portion of said window frame into operative or coal-receiving position for discharging the same through said window, and a lintel secured to said window frame and to said casing frame.

4. A combined window and coal hopper comprising in combination a window frame of a single piece bar bent to proper shape and of suitable cross section, a casing frame of sheet metal secured to said bar and projecting rearwardly therefrom, a coal hopper pivotally mounted at its inner edge on the sill portion of said casing frame and movable inwardly thereagainst into inoperative position and outwardly over the sill portion of said window frame into operative or coal-receiving position for discharging the same through said window, and a lintel of sheet metal secured to said window frame and said casing frame and provided with longitudinally disposed reinforcing ribs, the ends of said lintel projecting beyond the sides of said frames.

5. A combined window and coal hopper comprising in combination a window frame of single piece bar T-shape in cross section and bent to proper shape, a casing frame formed of sheet metal and secured to the laterally and inwardly projecting web portions of said window frame, a lintel secured to the upper web portion of said window frame and to portions of said casing frame and having its ends projecting beyond said frames, and a hopper hingedly mounted on the sill portion of said casing frame and movable outwardly over the sill portion of said window frame into a position above the window sill for receiving and discharging the coal through said window, said hopper being displaceable when not in use away from said window frame inwardly against the sill portion of said casing frame.

6. A combined window and coal chute comprising in combination a window frame of a single piece T-bar bent to proper shape,

a casing frame of sheet metal bent in U-shape secured to the inwardly projecting flange of said bar, a lintel of pressed metal secured to the inwardly projecting flange of the lintel portion of said window frame and to the in-turned ends of said U-shaped piece, and a coal hopper pivotally mounted on the sill portion of said casing frame and movable inwardly into a displaced position against the sill portion of said casing frame when not used, and adapted to be moved outwardly into extended position over the sill portion of said window frame to receive the coal.

In testimony whereof I hereunto affix my signature this 11th day of December, 1925.

FRANK MESKER.
